UNITED STATES PATENT OFFICE

HERBERT DAVID JACKSON AND FRANK WHITE, OF WALSALL, STAFFORDSHIRE,
ENGLAND

CLOSURE FOR BOTTLES, JARS, AND OTHER CONTAINERS

Application filed March 26, 1930, Serial No. 439,121, and in Great Britain March 26, 1929.

This invention relates to a new or improved closure for bottles, jars, and other containers, and has for its object to provide a closure which when first applied makes a positive seal both against leakage of the contents of the vessel and against unauthorized removal of the closure.

Any attempt to remove the closure results in the fracture or destruction of the locking seal so that the attempt is at once obvious and theft or substitution of the contents of the bottle or other container is positively prevented.

At the same time the efficiency of the closure for retaining the contents is not impaired so that after the closure has been removed by an authorized person it can be repeatedly removed and replaced during the consumption of the contents of the container.

A further object is to provide a closure for this purpose which can readily be employed for glass bottles or other vessels without necessitating the moulding of accurately shaped and spaced projections or recesses in the neck of the vessel.

According to our invention a cap or the like, which may have a screw, bayonet-catch, or like connection with the neck of a bottle, jar, or other container, carries a resilient tongue member projecting through an opening in the cap into engagement with a stop on the neck of the container.

The direction of projection of the tongue is such that in the application of the cap to the container it can ride freely over the stop or projection, but on any reverse movement the free end of the tongue member engages against the stop and the tongue member will be destroyed or broken off.

The stop may conveniently be the end of the screw-thread or of one of the bayonet grooves or projections with which the cap normally engages, these being moulded on the neck in the case of glass vessels. As it is difficult to ensure accuracy of the grooves on the glass with which projections on the cap engage in the case of a bayonet-catch type of fastening, the projections on the cap may be made after the cap has been applied and while

it is held under pressure against the neck of the vessel.

To avoid the necessity for moulding accurately shaped and spaced projections or recesses in the neck of a glass vessel the cap and the resilient tongue carried by it may engage with a tubular sleeve which is permanently secured on the neck of a bottle or the like as for example by rolling in its lower edge below an annular rib or shoulder on the neck, the sleeve being suitably keyed against rotation on the neck.

Some practical forms of our invention as applied to closures for bottles are illustrated by way of example in the accompanying drawing in which:

Figure 1 is a side elevation of a bottle neck fitted with a sealing cap in accordance with our invention.

Figure 2 is a side elevation of the bottle neck with the cap removed.

Figures 3 and 4 are side elevations of the cap with the resilient tongue respectively in place and broken off.

Figure 5 is a section on the line 5—5 of Figure 1.

Figure 6 is a perspective view of a modified form of cap.

Figure 7 is a perspective view of a modified construction employing a separate sleeve fixed upon the bottle neck, the cap being shown before application.

Figure 8 is a similar view showing the cap applied.

In the construction illustrated in Figures 1 to 5a is a flanged sheet metal cap provided with a cork or other seating washer against its end face. On one side of the cap is a rectangular opening *b* at one end of which is an outwardly pressed portion or boss *c*. A short length of curved resilient steel or other metal strip *d* is secured to the cap at one side of the opening *b* by punching a hole in the cap through a hole *e* in the strip so that the metal from the hole is clinched over on the outside of the strip and retains the strip in place. The other end of the strip *d*, which will hereinafter be referred to as the tongue member, extends through the opening *b* on the inside of the cap as shown in Figure 5. The bottle

neck *f* is formed with a peripheral groove *g* and an end flange *h* in which are formed two opposed slots leading into the groove *g*, one side of each slot being formed with a flat 6 radial face *j* and the other side being cut away to form an inclined face *k* for engagement by projections on the cap in the usual way.

The cap is adapted to be fitted over the 10 bottle neck with the free end of the tongue member abutting against one of the flat faces *j* as shown in Figure 5. The bottle is then placed in any suitable machine which applies end pressure to the cap to hold it tightly against the bottle neck, and opposed portions 15 of the free edge of the cap are pressed in as shown at *l* to form projections which engage under the shoulder *h* so that the bottle is tightly sealed. Any form of capping machine is suitable for this operation so long as 20 it has means for applying end pressure to the cap and for simultaneously pressing in portions of the cap flange.

To open the bottle the cap is turned in an 25 anti-clockwise direction, but immediately any such movement is commenced the free end of the tongue member *d* is forced against the face *j* so that end pressure is applied to it and the securing of the tongue member to the cap is broken so that the tongue member flies 30 off and cannot be replaced. The cap can now be turned until the projections *l* come opposite the slots in the shoulder *h* whereupon the cap can be lifted off. If all the contents of 35 the bottle are not used the cap can be replaced, and the projections *l* riding down the inclined faces *k* will bring the cap again into airtight contact with the bottle neck to retain and preserve the contents of the bottle.

40 Where it is possible to obtain standardization of the grooves and shoulders on the bottle necks the projections on the cap may be formed in the cap in the course of manufacture as shown at *m* in Figure 6. The cap is then applied in the same way as an ordinary 45 cap having a bayonet-catch connection with a bottle neck.

In the modified construction illustrated in 50 Figures 7 and 8 the cap engages not with the bottle neck but with a sleeve which is permanently secured in place upon a bottle neck. The cap is substantially the same as already 55 described, two opposed projections *n* being pressed in the sides to co-operate with grooves or slots in the sleeve. The sleeve *p* is of tubular form to fit over a collar or shoulder of substantial depth against which its in-turned upper edge *q* seats and above which are formed two opposed projections *r* on 60 the neck which enter notches in the edge *q* and hold the sleeve against rotation. The sleeve is provided with opposed bayonet slots *s* for engagement by the projections *n* on the cap, and with a gap or opening *t* for engagement by the spring tongue.

65 To fit this device to a bottle the cap and

sleeve are first assembled together in their normal engaged position and the assembly is placed upon the bottle neck. End pressure is then applied to the cap and the free lower edge of the sleeve is rolled in as shown at *u* 70 under the lower edge of the shoulder on the bottle neck so that the bottle is effectively sealed. The sleeve remains a fixture on the bottle neck but the cap can be removed in the ordinary way after breaking off the tongue member, and the cap can be replaced as often as desired to preserve the contents of the bottle.

75 We claim:

A closure for bottles, jars, and other containers comprising a flanged cap having an opening therein, projections on said cap, means on the neck of the container with which said projections cooperate to retain the cap in sealing engagement with the neck, a resilient tongue member of which one end is frangibly secured to the cap and the other end projects through said opening, and a stop 85 on the neck against which said tongue abuts for a purpose specified.

90 In testimony whereof we affix our signatures.

HERBERT DAVID JACKSON.
FRANK WHITE.
